UNITED STATES PATENT OFFICE.

THOMAS WHITEHEAD HAWKINS, OF RUABON, WALES.

DRYING MACHINE FOR WOOL AND OTHER MATERIALS.

Application filed August 4, 1923. Serial No. 655,725.

To all whom it may concern:

Be it known that I, THOMAS WHITEHEAD HAWKINS, a subject of the King of Great Britain and Ireland, and residing at Acre-
5 fair Engineering Works, Ruabon, in the county of Denbigh, Wales, have invented certain new and useful Improvements in Connection with Drying Machines for Wool and Other Materials, of which the following
10 is a specification.

This invention relates to apparatus for drying wool and other like substances or material.

In the drying of fibrous material it has hitherto been proposed to draw heated air through a chamber within which are located two perforated or like endless bands between which the material is conveyed through the chamber so that the air passes
15 through said bands on its way to the outlet. Such apparatus, however, is not satisfactory for drying wool and like material for the reason that the air will naturally seek the easiest way through and therefore
20 to a large extent passes through such parts of the bands as are not covered by the wool, and such parts as are covered to a less extent than others whereby it results that a large part of the wool in passing through
25 would be dried insufficiently or not at all.

The object of the present invention is to provide an improved form of wool drying machine which will obviate the defects and disadvantages of existing or hitherto known
30 machines, and the invention consists in a wool drying or like machine in which the wool or like material is conveyed through the apparatus between two perforated or like belts or bands characterized by the
35 feature that a plurality of independent controlled or guided supplies of air or other drying medium are simultaneously passed through the material during its passage from one end to the other of the machine.

40 The invention also consists in wool drying or like apparatus of the above character characterized by the feature that both endless bands extend beyond the end of the machine so that they are easily accessible for
45 cleaning from the exterior of the drying chambers while at the same time the whole of the space between the belts or bands will be visible from the exterior so that the condition may be readily ascertained before
50 fresh material is fed to the machine, this

being particularly desirable in connection with the drying of wool where it is important that different qualities or colours of wool should not become mixed.

The invention also consists in other de-
tails hereinafter pointed out in the claims.

The accompanying drawings illustrate one convenient form of machine in accordance with the invention:

Figure 1 being a side elevation, and 65

Figure 2 a plan, while

Figure 3 is a cross-sectional elevation on a somewhat larger scale.

In carrying my invention into effect when constructing my machine particularly for drying wool, I make it with a number of independent compartments *a* into which the dry air may be caused to pass and these compartments may be suitably constructed and arranged so as to make a series of spaces 70 or chambers through which the same layer of wool may pass in order that when it reaches the final or end compartment or chamber the wool may be adequately and properly dried with the necessary degree 75 of moisture removed therefrom.

I make my compartments preferably in the form of chambers, the upper portion of which may be circular or curved, as shown, so as to deflect the air when passing in 80 an upward direction and cause it to fall or traverse in an opposite or downward direction through the layer of wool that is passing through and beneath it when such a duplex action upon the wool is found nec- 85 essary.

I arrange beneath the compartments an air supply duct *b* having suitable valves or regulators *c* therein into which duct I deliver air from a fan or other blower *d* after 90 such air has left the blower and been heated and dried to a sufficient extent to enable it to be in the most satisfactory condition for absorbing the moisture from the wool through which it passes.

I provide my apparatus with a series of rollers *e* for the purpose of supporting and carrying moving aprons or belts *f*, *g*, and these rollers also serve to keep the chambers separate so that the heated air is prevented 95 as far as possible from escaping from one chamber to another without passing up or down through the material being treated. Between the two parallel moving belts I place the wool *h* (Figure 3) that is to be 100 105 110

dried or treated in my machine, the wool being fed on to the outside portion of the apron projecting beyond the machine by means of a conveyor *i* in order that it may 5 pass into the machine and be carried between the lower and upper belt surfaces which are travelling in the same direction for carrying forward the wool.

I cause the two open spaced or reticulated 10 aprons that are travelling in the same direction with the wool between them to deliver the wool at the outside of my machine at a position where the aprons pass over pulleys *k*, *l*, in order that they may travel 15 in the reverse direction through the machine to the pulleys *m*, *n* at the opposite end, providing any necessary supplementary guiding bearings or pulleys *o*. The pulleys at either or both ends of the aprons may 20 act as drivers for imparting the motion thereto.

In the drawing I have shown the pulleys *k*, *l* as the driving pulleys for the aprons, such pulleys being in turn driven by the 25 worm *p* and worm wheels *q* or by other suitable means. Further, each of the pulleys may be adjustable in its bearings for adjusting the aprons.

I cause the wool that is travelling upon 30 and between the moving belts which travel at the same uniform speed with the wool between their surfaces to be subjected preferably to an upward and downward current of dry or hot air, in order that moisture may 35 be removed therefrom, and the downflowing air may then pass into a duct or chamber *r* which leads back to the fan for supplying to some degree the air that is to be again in part used for drying purposes after the 40 moisture has been removed or has escaped therefrom. Such air may be returned to the fan by the pipe *s* and I may arrange in said pipe slots or openings *s*⁴ adapted to be wholly or partly registered with slots *s*³ 45 provided in an adjustable shutter ring *s*² so that any desired quantity of fresh air may be drawn in by the fan to compensate for any moist air which it may be inadvisable to return to the fan.

I may arrange my inlet duct which receives its hot or dry air from the fan chamber to pass along beneath the entire series of independent drying chambers with inlets for each drying compartment provided and 55 arranged thereupon, each inlet having its own controlling valve mounted therein. This common air supply duct I make of a narrower width at the bottom than the common outlet duct into which the outflowing 60 downward currents of the air are delivered in order that the machine may be self-contained and that the lower portion or casing may carry the inlet duct or common supply trough within that which forms the outlet or discharge trough, making the inlet duct 65

or trough to taper or be sufficiently enlarged to deliver air to the extreme width of the aprons that are passing through the machine.

I do not limit the application of my invention to any particular number of independent chambers into which the air is to be supplied and through which the moving latticed belts or aprons of any usual construction are to pass, but I modify the number and form of such drying chambers and the arrangement of the belts and rollers beneath them, together with the shape and configuration of the air inlet and outlet ducts, to suit the quantity of wool that is to be operated upon and the speed at which the same is to be delivered and passed through the machine. I make my machine with a number of independent or associated chambers and each of them may have the alternate upward and downward movement of the air, when such is employed, and the forward and backward passage of the belts, but the two forward surfaces of the belts always having between them the wool that is to be dried when such are passing through the multiple drying chambers.

I employ any suitable form of belting, apron, fan or blowing apparatus for use in connection with my improved quick speed drying machine and utilize any well-known form of heater or device for drying or giving heat to the air before it passes through the travelling aprons with the wool arranged between such. I modify the form and disposition of my carrier and ducts to suit the requirements of any material that is to be dried, in the manner substantially as described when operating upon wool.

Having now described my invention, what 105 I claim as new and desire to secure by Letters Patent is:—

1. In a drying apparatus for wool and the like, a series of drying chambers, travelling open-work carriers passing through said chambers to carry the material to be treated therethrough, a fan, an inlet duct for the drying chambers communicating with said fan and having a plurality of outlets, each outlet terminating in proximity to a portion of the carrier located in one drying chamber, and air outlet means communicating with the portion of the drying chamber lying on the same side of the carriers with the air duct outlets.

2. An apparatus as claimed in claim 1, characterized in that the inlet duct for the air is surrounded by the outlet means, the latter leading the air back from the drying chambers to the fan.

3. In an apparatus for drying wool and the like, a series of drying chambers, travelling open work carriers passing through said chambers to carry the material to be treated therethrough, a fan, an air inlet duct for

the drying chambers communicating with said fan and having a plurality of outlets, each outlet terminating in proximity to a portion of the carrier located in one drying chamber, and supporting rollers for the carriers arranged adjacent the opposed sides of each of the outlets of the inlet duct whereby to compel the air issuing from said outlets to pass through the carriers and the material thereon.

4. An apparatus for drying wool and the like in which the wool is conveyed through the apparatus between two foraminous carriers, characterized by the provision of means for directing streams of fluid drying medium simultaneously through the material during its passage from one end to the other of the machine, and means for independently controlling the respective streams of drying medium.

5. In an apparatus for drying wool and like material, a plurality of drying chambers arranged side by side, traveling open-work carriers passing through said chambers to carry the material to be treated there-

through, means arranged on one side of said carriers for directing streams of air through portions of the carriers located within the respective chambers, a fan, a common supply pipe connecting said fan with the several air directing means, means for causing the air passed through the carriers and the material thereon to return to the chambers on the first mentioned side of the carriers, said chambers having communication with one another on the first mentioned side of said carriers, and means for returning the air from the communicating portions of said chambers to said fan.

6. An apparatus as claimed in claim 1 characterized in that the fan, air inlet duct, chambers and air outlet means constitute a closed circuit for the air, and means permitting and regulating the admission of air to said circuit.

In testimony whereof I have signed my name to this specification.

THOMAS WHITEHEAD HAWKINS.
